UNITED STATES PATENT OFFICE.

JULIO E. LANFRANCO, OF VALPARAISO, CHILE.

GUIDE FOR CLEANING-RODS OF FIREARMS.

1,251,247.

Specification of Letters Patent. Patented Dec. 25, 1917.

Application filed July 13, 1917. Serial No. 180,345.

To all whom it may concern:

Be it known that I, JULIO E. LANFRANCO, a citizen of the Republic of Chile, residing at Valparaiso, Chile, have invented certain new and useful Improvements in Guides for Cleaning-Rods of Firearms; and I do hereby declare the following to be a full, clear, and exact description of the invention, such as will enable others skilled in the art to which it appertains to make and use the same.

My invention is a guide and operating handle for cleaning rods, so constructed that, when the cleaning rod is pushed or drawn through the bore of a rifle, it will follow the rifling of the bore.

The invention is illustrated in the accompanying drawings, in which—

Figure 1 shows the device assembled;

Fig. 2 shows a section taken on the line 20 2—2 of Fig. 1;

Fig. 3 shows the inner cylindrical member of the device, with parts in section, and

Fig. 4 shows the outer handle or sleeve member, in central section.

As shown in the drawing, the guide is made up of an inner cylindrical member 1, which is to be secured to the cleaning rod, and an outer sleeve or handle member 2.

The inner cylindrical member 1 is about 30 17.5 centimeters long. At one end it has a hole 3 of about 6.5 millimeters diameter in which the end of the cleaning rod is placed and secured by means of a pin or piece of wire 4, extending through a small hole.

The inner cylindrical member 1 has a helical portion 5, about 5.5 centimeters long, and a smooth cylindrical portion 6, about 8.5 centimeters long, and 7 millimeters in diameter. The helical portion has four helical 40 threads 7 which run from right to left.

The outer sleeve member or handle 2 is a hollow cylinder about 9 centimeters long, having at one end an opening 8 which slides on the cylindrical portion 6 of the inner member 1, and at the other end four teeth 9 which act against the four helical threads 7.

The threads 7 have an inclination sufficient to permit the teeth 9 to slip thereon, so that, as the handle or sleeve 2 is pushed 50 along the cylindrical member 1, it will cause the latter to turn.

The sleeve 2 is held on the cylindrical member 1 by a nut 10 screwed on the threaded end 11 of the member 1, so that the sleeve

cannot be removed without removing this 55 nut.

When the guide is secured to a cleaning rod, and the cleaning rod pushed or drawn through the bore of the rifle by grasping the sleeve 2 and pushing or pulling thereon, the 60 action of the teeth 9 on the threads 7 will cause the cleaning rod to have both a longitudinal and rotary movement, so that it will follow the rifling in the bore, and more effectively clean the same. The handle or 65 sleeve 2 thus serves both to push the cleaning rod and to turn it. The four teeth take the place of complementary screws or threads, operating on the helical threads 7, but have the advantage of decreasing the friction so 70 that the slipping or sliding on the threads 7 is made easier.

The inclination of the threads 7 is such that the mere pushing or pulling on the handle or sleeve 2 will cause the cleaning rod 75 to turn as it advances in the rifle, and to follow the riflings thereof.

My invention has the following advantages:

It can be attached to cleaning rods without 80 destroying or modifying them.

It operates mechanically, making the cleaning rods turn as they advance in the bore of the rifle.

Its operation is sure and accurate. 85

It is simple and easy to construct, as well as easy to assemble and repair.

It can be made of iron or other metal which is cheap and abundant.

Its size is such (only about 17.5 centimeters) that it occupies only a little space.

Its operation requires a straight pushing of the cleaning rod which nevertheless rotates as it advances. A turn of the handle corresponds to a turn in the spiral rifling. 95

Its operation is simple and does not require any experience, but only a simple and single explanation.

It consists of only two operating parts, which slip or slide on each other with a relative spiral movement. 100

Its action is based on the spiral or helical slipping, corresponding to the measure of the rifling.

It operates positively, somewhat in the 105 nature of a screw driver.

Inasmuch as the cleaning rod is turned as it advances, so that it follows the rifling of

the rifle, less strength is required to force the cleaning rod through the rifle.

Having thus described my invention, what I claim is:

5. 1. A guide for cleaning rods of fire arms, made up of a short rigid member provided with means for securing the end of the cleaning rod thereto and having helical threads thereon, and an outer handle or 10 sleeve member slidable on the inner member and having teeth coöperating with the helical threads, the pitch of the threads and the relative helical action of the inner member and sleeve with respect to each other being 15 such that, when the sleeve is used to push or pull the cleaning rod, a turn of the handle on the inner member corresponding to the pitch of the thread, and the resulting slipping of the teeth on the spiral thread, 20 will cause the cleaning rod to turn or rotate as it advances in the bore of the fire arm and follow the riflings therein.

2. A guide for cleaning rods of fire arms,

made up of a short rigid member having means for securing the end of the cleaning rod thereto, said member having a plurality of helical threads extending a portion of its length and having a portion of its length cylindrical, and an outer handle or sleeve member having one end thereof reduced and 25 slidable on said cylindrical portion, and having the other end thereof provided with a plurality of teeth coöperating with the helical threads, together with means for retaining said sleeve on said inner member, 30 the pitch of the threads and the relative helical action of the inner member and sleeve being such that a turn of the handle on the inner member corresponding to the pitch of the thread will cause the cleaning rod to turn or rotate as it advances in the bore of the fire arm and follow the riflings 35 therein.

In testimony whereof I affix my signature.

JULIO E. LANFRANCO.
